UNITED STATES PATENT OFFICE.

ARTHUR WILZIN, OF ST. OUEN, FRANCE, ASSIGNOR TO E. W. BLISS COMPANY, OF BROOKLYN, NEW YORK, A CORPORATION OF WEST VIRGINIA.

FEED-CONTROLLING MECHANISM FOR PUNCHING-PRESSES.

1,121,883.

Specification of Letters Patent.

Patented Dec. 22, 1914.

Application filed January 30, 1914. Serial No. 315,403.

To all whom it may concern:

Be it known that I, ARTHUR WILZIN, a citizen of the United States, residing at present in St. Ouen, Seine, France, have invented certain new and useful Improvements in Feed-Controlling Mechanism for Punching-PresSES, of which the following is a specification.

The present invention relates to improvements in hand-actuated staggering feeds as applied to punching presses for the purpose of blanking or simultaneously blanking and shaping out of sheets, objects such as disks or boxes with a view of reducing to a strict minimum, the scrap between adjoining cuts by interposing the cuts of the successive parallel rows in the sheet.

The purpose of the invention is to render less liable to wear the organ which determines the lateral distance between the punchings in the same row; also and by the same means to allow the sheet carrier to accommodate itself to the height variations of the dies arising from the wear of its cutting edges, and in its preferred form, to render it possible for the operator to not interrupt the continuous running of the press, which interruption has been inevitable at the end of each row up to now in feeds of this kind owing to the fact that a double hand actuated manipulation had then to be performed, namely releasing of the mechanism which determines the distance of the sheet carrier from the tool and its lateral shifting by one half of the distance between successive lateral cuts so as to determine the "interposed" or "staggered" position. This interruption, involving the loss of five or six press strokes at each end of a row, accounts for at least 25% less output than would otherwise be possible. The feed in its preferred form as described herein renders this interruption unnecessary, thus greatly increasing the output.

The invention is represented, but only by way of example, in the annexed drawing, in which:

Figure 1 is a perspective view of the new apparatus. Fig. 2 is a section of a detail, made on a larger scale. Figs. 3 and 4 represent in elevation and in plan a variation.

In the drawing manually actuated apparatus for cutting metallic sheets in staggered rows is shown. In Figs. 1 and 2, the sheet or metallic leaf *a*, which is presented to the press *b*, is shown held by two pincers *c* carried by a carriage *d*; a lever *d'* allows of opening or closing these pincers at will. A roller *e* resting upon the feed table *f* of the machine supports this carriage or sheet carrier and allows of shifting it without effort. This shifting is effected by means of a handle *g* which the workman holds as the drawing shows.

The carrier *d* is guided by shaft *h* which presents cylindrical bosses *h'*, *h''*, Fig. 2; the separation of these bosses, reckoned from axis to axis, is equal to the separation of the centers of the holes to be pierced. The part *h* can be considered as a rack-bar in the form of a shaft, circumferentially notched to suit the lateral division or separation of the centers. The shaft has associated with it means for imparting to it varying positions around its axis so as to present successive varying contact surfaces to the action of the dog (presently to be described) which coöperates with the divisional notches, thus reducing the tendency to wear. The sheet carrier is hand controlled and is oscillatorily disposed on the rack-bar or notched shaft. The shaft is shown disposed transversely of the machine, and the carrier, provided with sheet-holding means, is mounted on such shaft for movement transversely of the machine, there being means associated with the shaft for controlling the transverse movement of the carrier.

A dog illustrated in the form of a bolt *i* capable of sliding in a socket *j* of the carriage *d* is supported by a spring *i'* against the shaft *h*, for engaging the rack-bar or notches of such shaft; a pliable transmission actuated by the press itself raises the bolt at each blow of the press. The dog or bolt is adapted to swivel upon the shaft, the position of the dog axially of the shaft remaining constant.

Shaft *h* carries two toothed wheels *l* keyed upon it; these wheels or pinions mesh with the two parallel fixed racks *m*. The pinions serve to rotate the shaft and cause its move-

ment longitudinally of the machine to be parallel with itself. It tends to be brought back against the workman by the counter-weights n acting against the cables n' passing over pulleys n^2 .

Upon one extremity of the shaft h is idly mounted a pawl t the extremities of which can engage in the notches o which present a straight edge p forming one of the borders of the table. These notches are at a distance equal to the separation of the rows of holes. The pawl can be disengaged by means of a lever r .

Plates q accompanying the shaft h prevent the latter from being displaced vertically.

The operation is as follows:—Assume that the pawl t be engaged in a notch o and that the car d is at one extremity of the shaft h , for example, at its left extremity. The workman then acts upon the handle g exerting thereby a traction toward the right (toward the left in Fig. 2). At the moment of the stroke of the press the spring controlled dog i is automatically raised at the blows of the press, and the sheet carrier ceases for an instant to be held. Under the effect of the pull of the workman the sheet carrier is shifted toward the right, but it is stopped by the dog i which redescends and hits against the following boss. The car is thus then shifted along the shaft h , between two blows of the press, by a length equivalent to the distance of two holes of the plate to be cut out. When the sheet carrier reaches the right extremity of the division, the workman pushes before him until the pawl t falls into the following notch where it rests supported under the action of the counter-weights. The workman then pulls upon the handle g in the opposite direction, that is to say, toward the left, and the sheet-carrier advances division by division toward the left as before. But as the dog i now abuts against the other faces of the bosses h^1 , h^2 , h^3 , the blows of the punch are now "staggered" as regards those of the preceding row. The table f can be horizontal or inclined. If it is horizontal, as in the case of the drawing, the throwing out of the pieces formed is brought about by a blast of air coming from the nozzle s . If it is inclined, the throwing out is done by gravity. As is understood by what precedes the operator has only to act upon the handle g in the desired direction; there is only then a single hand in use. This simplification of the movements to be effected allows of working with great rapidity. The return empty is also very rapid. As the car can turn about the division shaft the new arrangement is easily adapted to all tools although the level thereof may be variable.

At each advance of the sheet-carrier parallel

to the racks, the shaft h turns upon itself and this changes the point of contact with the dog i and diminishes the wear. The shaft h guided by the pinions l meshing with the racks remains perfectly parallel to itself. Finally the surface of the table is perfectly smooth and the sheet does not run the risk of "butting" during the various movements of the carrier.

The invention in its preferred form is represented by Figs. 3 and 4, where the feed-carrier is constantly urged toward the tool by two counter-weights n . The pawl t is in the form of a hook and engages in the notches o of a suitable form made in the straight edge p . The two plates q carry a shaft u on the extremity of which is keyed a lever v , which controls by the intermediation of a small rod or link v' , the pawl t . The other levers w are fixed upon the shaft u at points suitably chosen and each carries a finger y .

When the car carrying the pincers, the sheet carrier, reaches the end of the course upon the rack-bar or shaft, and when its dog or bolt i , controlled by the pliable transmission, is raised, a small lever z carried by this bolt, abuts against the finger y of the lever w , raises it also and brings about the disengagement of the pawl t ; the counter-weights n carry the ensemble forward one division.

It is evident that at each extremity of the course of the sheet-carrier, this movement being automatically produced obviates a special effort on the part of the workman and allows a complete punching of the sheet without the necessity of stopping the press at the end of each row.

The arrangements above are given only by way of example; the shapes, dimensions and arrangements of detail can vary according to circumstances without changing the principle of the invention.

I claim:

1. In a device of the character specified, the combination with a punching press of a sheet carrier, a rack bar in the form of a shaft circumferentially notched to suit the lateral divisions, a dog for engaging the said notches, and the carrier being adapted to swivel upon such shaft to accommodate itself to height variations of the die of the press, the position of the dog axially of the shaft remaining constant.

2. In a device of the character specified, the combination with a punching press of a sheet carrier, a rack bar in the form of a shaft circumferentially notched to suit the lateral divisions, a dog for engaging the said notches, and the carrier being adapted to swivel upon such shaft to accommodate itself to height variations of the die of the press, the position of the dog axially of the shaft remaining constant, and means of im-

parting to said shaft varying positions around its axis so as to present successive varying contact surfaces to the action of the dog which coöperate with its divisional 5 notches, thus reducing their tendency to wear.

3. In a device of the character specified, the combination with a notched division shaft of a sheet carrier oscillatorily disposed 10 on said shaft, a dog carried by said carrier for engaging the notches of the shaft, means for holding the shaft in proper position relatively to said punching tool, and means for actuating said locking device for releasing 15 the shaft and the carrier at the end of each row of punchings.

4. In a device of the character specified, the combination with a punching press of a circumferentially notched shaft, a sheet carrier mounted upon said shaft, a dog associated with said carrier for engaging the notches of the shaft, racks upon the press, and pinions fast upon the shaft and meshing 20 with the racks for changing the wearing 25 surfaces of the notches presented to the dog.

5. In an apparatus for punching sheets in staggered rows, the combination with a carrier provided with sheet holding means, of a shaft disposed transversely of the machine 30 and upon which shaft the carrier is mounted for movement transversely of the machine, means for guiding said shaft longitudinally of the machine, and means associated with the shaft for controlling the said transverse 35 feed movement of the carrier.

6. In a device of the character specified, the combination with a rack shaft, means for moving the said shaft parallel to itself, a carrier mounted upon said shaft and adapted 40 to traverse the same, a spring pressed dog for engaging the rack, and means for automatically releasing the dog at the successive blows of the press.

7. In a device of the character specified, 45 the combination of a rack bar in the form of a shaft provided with circumferential notches, means for moving said rack bar parallel to itself, a carrier mounted upon said rack bar, a dog for engaging said 50 notches, and means for raising the dog at the blows of the press.

8. In a device of the character specified, 55 the combination with a rack bar in the form of a shaft provided with circumferential notches, means for moving the said rack bar parallel to itself, a carrier mounted upon said rack bar, a dog for engaging said notches, means of raising the dog at the 60 blows of the press, and a handle upon the carrier.

9. In manually actuated apparatus for cutting metallic sheets in staggered rows, the combination with a carrier provided with sheet holding pincers, a notched shaft 65 mounted upon the machine for movement

parallel to itself, a spring controlled dog, and means actuated by the press for automatically raising the dog at the blows of the press for permitting the advance of the carrier step by step upon the shaft. 70

10. In a device of the character specified, the combination with a rack bar in the form of a shaft provided with circumferential notches, means for moving said rack bar parallel to itself, a carrier mounted upon 75 said rack bar, a dog for engaging said notches, means for raising the dog at the blows of the press, pinions carried by the shaft, racks for the engagement of said pinions whereby the shaft is rotated upon 80 the forward movement of the carrier.

11. In a device of the character specified, the combination with a rack bar in the form of a shaft provided with circumferential notches, means for moving said rack bar 85 parallel to itself, a carrier mounted upon said rack bar, a dog for engaging said notches, means for raising the dog at the blows of the press, means for controlling the longitudinal movement of the carrier, 90 and means associated with the dog for releasing the same at the end of each row of punchings.

12. In a feed controlling mechanism for 95 punching presses the combination with a rack shaft, of a sheet carrier mounted thereon, a dog associated with the carrier for engaging the teeth of the rack, means for actuating the dog in proper timing relatively to the punching of the sheet, means 100 for controlling the longitudinal movement of the carrier, and means associated with the dog for actuating the same upon the limits of the lateral excursions of the carrier.

13. The combination with a punching 105 press, of a feed table, a rack bar disposed transversely thereof, means for guiding the rack bar longitudinally of the table, a carriage mounted on the rack bar, a dog on the carriage for engaging the rack bar, means 110 for moving the carriage and rack bar forward longitudinally of the feed table, a pawl and rack associated with the carriage and the feed table for controlling the forward advance of the carriage, means for 115 raising the said dog at the successive blows of the press, and means associated with such dog for raising the said pawl at the completion of each transverse row of punchings.

14. In a device of the character specified, 120 the combination with a punching press, of a feed table, a rack bar mounted transversely thereof, means for moving the rack bar longitudinally of the feed table, a carriage mounted upon said rack bar, a dog on the 125 carriage for engaging the notches of the rack bar, means for raising the dog at successive actions of the punch, a pawl carried by the carriage, a rack upon the feed table for engaging such pawl for controlling the 130

forward advance of the carriage, means located at each end of the rack bar and located in position to be engaged by the dog in its elevation after completing the last 5 punch in a row of punchings for actuating the pawl and permitting the advance of the carriage.

In witness whereof, I have hereunto signed my name in the presence of two subscribing witnesses.

ARTHUR WILZIN.
